UNITED STATES PATENT OFFICE.

AXEL OLFORT, OF CHICAGO, ILLINOIS.

WINDOW ADJUSTER.

1,419,893.

Specification of Letters Patent. Patented June 13, 1922.

Application filed April 5, 1921. Serial No. 458,653.

To all whom it may concern:

Be it known that I, AXEL OLFORT, a citizen of the United States, residing at Chicago, in the county of Cook and State of Illinois, have invented new and useful Improvements in Window Adjusters, of which the following is a specification.

This invention relates to window adjusters and an object of the invention is to provide 10 a device which is simple in construction and may be easily attached to or detached from a window structure, the said device being operable for simultaneously moving the upper and lower sash a predetermined distance 15 to permit the circulation of air through a room and also to prevent further movement of either of the window sash, from the outside or without operating the adjuster structure, thereby permitting the occupant of a 20 room or building to adjust a window to permit circulation of air in a room and leave the building in which the arm is located without fear of anyone maliciously entering 25 the room through the window and still permit the free circulation of air through the room at all times.

Another object of the invention is to provide a window adjuster as specified, which is constructed so that it may be easily disconnected 30 from a window, when it is desired to clean or paint the woodwork of the window structure or for any other purpose and one which may be easily replaced when desired.

35 Other objects of the invention will appear in the following detailed description and in the accompanying drawing wherein:

Fig. 1 is a fragmentary section through a window structure showing the improved 40 adjuster applied and showing the window sash closed.

Fig. 2 is a view similar to Fig. 1 showing the window sash in a partly open position.

Fig. 3 is a horizontal section on the line 45 3—3 of Fig. 1.

Fig. 4 is a detail cross section taken on the line 4—4 of Fig. 3.

50 Fig. 5 is a detail section illustrating the connection of the adjuster with a window sash.

Referring more particularly to the drawing the window sash 1 and 2 which are slideable vertically one past the other in the usual manner, are provided with recesses 3 cut in 55 their frames or sash 4. The recess 3 in the lower sash 2 is positioned adjacent to the up-

per edge of the lower sash while the recess 3 in the upper sash 1 is positioned nearer the lower edge of the sash within its upper edge so as to permit the provision of an adjuster 60 which is relatively light in weight and comparatively simple.

The sash 1 and 2 have plates 5 attached thereto about the recesses 3 and these plates are perforated as at 6 having the portions 65 about the edges of the perforations inturned as shown at 7. The hook shaped ends of the arms 9 and 10 of the adjuster engage through the openings 6 and about the inturned edges 7 as clearly shown in Fig. 5 of the drawing 70 for connecting the arms 9 and 10 to the sash 1 and 2. The arm 9 is pivotally connected as at 11 to the hand lever 12 at one side of the pivot of the hand lever while the arm 10 is pivotally connected as shown at 14 to 75 the lever 12 at the opposite side of the pivot 13 of the lever as clearly shown in Figs. 1 and 2 of the drawing so that when the hand lever 12 is moved upon its pivotal connection 13 the arms 9 and 10 will be moved in 80 opposite directions to move the sash 1 and 2 in opposite directions for either opening or closing the window. In Fig. 1 of the drawing the sash are illustrated as closed and it will be noted that the pivot 14 is positioned 85 at one side of a vertical line bisecting the axis of pivotal movement of the lever 12 while the pivot pin 11 is positioned on the opposite side of said line thereby providing locking of the window sash 1 and 2 and preventing 90 their independent or simultaneous movement independent of operation of the hand lever 12. The same condition exists when the position of the hand lever is reversed, i. e. when it extends upwardly, therefore, the sash 1 and 2 are locked in open position so that they cannot be opened further either independently or simultaneously without disconnecting the arms 9 and 10 from the respective sash.

95 In Fig. 2 of the drawing 100 the lever 12 is shown only partly operated for the purpose of illustration but it is to be understood that when leaving the room in which the structure is mounted the lever 12 is to be moved until it extends substantially 105 vertical upwardly from its pivot 13 at which time it engages the sash 1 in much the same manner in which it is shown in engagement with the sash 2 in Fig. 1 of the drawing.

110 The hand lever 12 is pivotally supported upon a bracket 16 which is attached to the window frame 17 in any suitable manner

and which provides an overhanging portion 18 recessed longitudinally from its free outer end as shown at 19 to permit the insertion of the pivot and clamping stud 20 of the 5 lever 12 therein. The lever 12 is provided with a lateral offset portion 21 which engages in a corresponding offset portion 22 formed in the overhanging portion 18 of the bracket 16 and these offset portions are 10 clamped in engagement with each other by a clamping nut 23 mounted upon the threaded end 24 of the pivoting stud 20. The frictional gripping engagement of these outstruck portions is such as to permit relative free pivotal movement of the lever 12 to prevent the offset portion 21 from springing or moving out of the offset portion 22 until the clamping thumb nut 23 is moved outwardly to release the outstruck portion 15 21 at which time pressure against the under surface of the overhanging portion 18, by the lower clamping head 25 is relieved and the entire pivot structure 13 may be slipped outwardly through the recess 19 for disconnecting the lever 12 from the bracket structure 16, when it is desired to detach the adjuster. The portion 26 of the stud 20, which 20 engages in the slot 19, is rectangular in cross section to prevent pivotal movement of the 25 stud 20 during movement of the lever 12. In detaching the adjuster, sash 1 and 2 are moved towards each other into substantially the position illustrated in Fig. 2 of the drawing and after the stud 20 has been removed 30 from its operative connection with the bracket 16 the lever 12 is slightly operated to permit the arms 9 and 10 to be rocked sufficiently to withdraw the hooks 8 from the recesses 3.

40 The reverse action takes place when remounting the adjuster upon the window.

It is, of course, to be understood that the invention may be constructed in various other manners and the parts associated in 45 different relations and, therefore, I do not desire to be limited in any manner except as set forth in the claims hereunto appended.

Having thus described my invention what I claim is:

50 1. In a window adjuster, the combination with a pair of slidable sash of a pivotally mounted hand lever, arms pivotally connected to said hand lever upon opposite sides

of its pivot, the pivotal connections between said arms and said lever being positioned 55 upon opposite sides of the line bisecting the axis of pivotal movement of the lever whereby said sash will be locked against movement when said hand lever is positioned at either terminal of its movement.

2. In a window adjuster, the combination with a pair of slidable sash, of a pivotally mounted hand lever, arms pivotally connected to said lever upon opposite sides of its pivot, said sash provided with recesses, a 60 plate mounted over said recesses and perforated, and hooks formed on the ends of said arms and engaging in said recesses for adjusting said sash upon pivotal movement of said lever, the pivots of said arms and said 65 lever being positioned upon opposite sides of a line bisecting the axes of pivotal movement of the lever whereby said sash will be locked against movement when said hand 70 lever is positioned at either terminal of its 75 movement.

3. In a window adjuster, a bracket, a pivoting stud detachably carried thereby, a hand lever pivotally mounted upon said stud and provided with an outstruck portion, said 80 bracket provided with an outstruck portion for receiving the outstruck portion of said lever, a clamp for clamping said outstruck portions in engagement to permit pivotal movement of said lever, and prevent detaching movement of said lever from the bracket, and window sash operating arms pivotally 85 carried by said lever.

4. In a window adjuster, an operating bracket, a pivoting stud detachably carried 90 thereby, a hand lever pivotally mounted upon said stud and provided with an outstruck portion, said bracket provided with an outstruck portion for receiving the outstruck portion of said lever, a clamp for 95 clamping said outstruck portions in engagement to permit pivotal movement of said lever and prevent detaching movement of said lever and bracket, window sash operating arms pivotally connected to said lever 100 upon opposite sides of its pivot and upon opposite sides of a line bisecting the axis of pivotal movement of the lever.

In testimony whereof I affix my signature.

AXEL OLFORT.
